SAFETY DEVICE FOR SHIPS' PROPELLER SHAFTS

Horace Edward Christopher Walpole,
Epsom, EnglandApplication May 7, 1943, Serial No. 486,093
In Great Britain May 27, 1942

6 Claims. (Cl. 115—34)

This invention relates to ships' propeller shafts and has for its object to provide a new or improved safety device to prevent the entry of water into a ship, boat or the like should the propeller shaft break and slip out through the bearing in the stern of the hull, leaving space for the inrush of water.

According to the present invention I provide a collar or flange fixed to or integral with the propeller shaft near to its bearing in the stern of the hull and I enclose the collar or flange in a casing extending around the shaft rearwardly up to the front end of the propeller shaft bearing in the hull and forwardly beyond the said collar or flange whereby if the shaft breaks rearwardly of the collar or flange and the propeller and broken off portion of the shaft leave the ship the inrushing water is checked by the casing after flooding it whilst if the shaft breaks forwardly of the collar or flange the propeller and broken off portion carrying the collar or flange move rearwardly until the rear face of the said collar or flange makes sealing contact with the rear wall of the surrounding casing.

One embodiment of the invention is illustrated in the accompanying drawings in which:

Figure 1 is a longitudinal sectional elevation and Figure 2 is a plan view of a portion of a propeller shaft in combination with the collar or flange and the enclosing casing according to the invention.

Figure 3 is an end view of the shaft in section and the exterior of the casing in elevation.

Figure 4 is a cross sectional view on the line 4—4 of Figure 1.

Figure 5 is a fragmentary sectional view of a modification in which the propeller shaft and the flange thereon are integral.

The collar or flange *a* is shown clamped onto the propeller shaft *b* and completely enclosed by the casing *c* of suitable shape or design. The casing *c* is mounted around the shaft extending through the stern *A* and bearing *A'* of the hull, with the rear end *d* of the casing close up to where the propeller shaft would become bare at *e* inside the hull so as to make a watertight joint there. The front end *f* of the casing is connected in a watertight manner to the next bearing (not shown) or is made watertight around the propeller shaft at *g* as hereinafter described. Between the two ends *f* and *d* of the casing it is considerably larger in diameter so as to allow space for the collar or flange *a* to revolve inside with a good clearance as shown at *i*. The collar or flange *a* can be made in one, two,

or more parts and be secured to the shaft by any suitable means such as bolts and nuts as shown at *j*. Alternatively the said collar or flange can be made part of the propeller shaft *b*, as shown at *a'* in Figure 5, by being turned on the said shaft during manufacture, and can be any suitable shape or design. An inspection plate or cover *k* can be fixed at the top of the casing as shown or in any other suitable position, and can be large enough to permit of attaching or removing or otherwise attending to the collar or flange from inside the hull.

The said collar or flange *a* has a disc shaped portion presenting an annular surface *l* facing a similar raised surface *m* on the inside of the rear end wall of the casing. Should the propeller shaft break at any place between its collar or flange *a* and the engines or driving force, the propeller shaft would slip out only as far as the collar or flange would allow by making contact between the surfaces *l* and *m*. The surface *l* would strike the surface *m*, thus preventing the propeller shaft from passing out of the bearing at the stern of the ship. Should the propeller shaft break or become detached anywhere along it between the points *n* and *o*, the shaft would slip out, thus allowing the entry of water but only into the casing *c* as far as *p*, the remaining section of the propeller shaft *b* still being in position.

The casing from *p* to *s* can have a small clearance with respect to the shaft, the diameter of the bore being slightly larger than the diameter of the shaft, and so give no resistance to the rotation of the shaft, yet at the same time preventing appreciable flow of water. This space can also be filled with grease or any other suitable substance to prevent the trickle of water through the clearance space, the grease being retained by small end collars *t* and *u*. A grease cap *v* is fixed for the purpose of adding grease. Should the casing be extended beyond *f* by attachment to the next bearing of the shaft, the collar *t* need not be used and the clearance around the shaft can be of appreciably larger diameter than the outside diameter of the shaft so as to ensure absence of contact and avoid resistance to rotation of the shaft.

What I claim is:

1. The combination with a ship's propeller shaft and its bearing in the stern of the ship's hull of a collar on the said shaft near to the said bearing and inside the stern of the hull and a casing enclosing the said collar and extending around the shaft rearwardly up to the front end

of the propeller shaft bearing in the hull and forwardly beyond the said collar or flange, and means for forming a water seal as between the internal surface of said casing and the rear face of said collar, whereby if the shaft breaks rearwardly of the collar or flange and the propeller and broken off portion of the shaft leave the ship the inrushing water is checked by the casing after flooding it whilst if the shaft breaks forwardly of the collar or flange the propeller and broken off portion carrying the collar or flange move rearwardly until the rear face of the said collar or flange makes sealing contact with the rear wall of the surrounding casing.

2. The combination according to claim 1 in which the collar is integral with the propeller shaft.

3. The combination according to claim 1 in

which the collar is in sections and attached to the propeller shaft.

4. The combination according to claim 1, including a disc portion with annular sealing surface on the collar and an opposing sealing surface on the interior of the rear wall of the casing.

5. The combination according to claim 1, in which there is appreciable clearance space between the propeller shaft and the surrounding surface of the front end wall of the casing, and means at each end of the annular clearance space whereby grease may be retained in said space.

6. The combination according to claim 1, in which the casing comprises a body portion and a removable cover plate.

HORACE EDWARD

CHRISTOPHER WALPOLE.
